UNITED STATES PATENT OFFICE.

CHARLES H. SCHOPBACH, OF AURORA, ILLINOIS.

CORSET.

1,133,824.

Specification of Letters Patent.

Patented Mar. 30, 1915.

Application filed November 27, 1912. Serial No. 733,785.

To all whom it may concern:

Be it known that I, CHARLES H. SCHOPBACH, a citizen of the United States, and a resident of Aurora, in the county of Kane and State of Illinois, have invented certain new and useful Improvements in Corsets; and I do hereby declare that the following is a full, clear, and exact description thereof, reference being had to the accompanying drawings, and to the letters of reference marked thereon, which form a part of this specification.

This invention relates to improvements in corsets, and particularly to that type of corsets as are provided with a ventilating section or sections.

The principal object of the invention is to provide a simple and efficient ventilated corset, adapted to be economically constructed, and a simple and efficient method of making the same.

A further object of the invention is to provide a ventilating or openwork section or strip for corsets comprising a series of transverse strips having spaces therebetween and provided with longitudinal, or upwardly and downwardly extending strips secured to the opposite end portions of the transverse strips, and adapted to hold the latter in proper position during the operation of securing the sections to the main body portion of the corset, and also adapted to connect the adjacent edges of the main body portion of the corset and to form pockets for receiving and holding in place suitable stays or ribs of stiffening or reinforcing material and for guiding the latter in the operation of inserting them into position to extend upward and downward along the opposite marginal portions of the openwork section or sections.

Other and further objects of the invention will appear from an examination of the following description and claim and from an inspection of the accompanying drawings.

The invention consists in the features, combinations, and details of construction herein described and claimed.

In the accompanying drawings, Figure 1 is a view in elevation of a piece of lattice-work or openwork, comprising a series of transverse strips and a series of upwardly and downwardly extending, or longitudinal strips attached to or connected with the transverse strips and adapted to hold the

same in position, and shows a plurality of the longitudinal strips as they appear before being cut longitudinally into two separate parts each adapted to form a side strip for a different ventilating or openwork section; Fig. 2, a similar view of a portion of a ventilating or openwork section showing the same as it would appear after being cut from the connected sections of a piece of openwork material, such as is shown in Fig. 1; 60 Fig. 3, a fragmentary view in elevation of a portion of a corset provided with a ventilating or openwork section constructed in accordance with my invention and improvements with parts broken away to show the 65 construction of the article and particularly the manner of connecting the transverse strips or portions of the ventilating or openwork section and the upwardly and downwardly extending strips and stays; Fig. 4, 70 75 a horizontal, sectional view, taken on line 4 of Fig. 3; and Fig. 5, a view of a modified form of ventilating or openwork strip comprising transverse and upwardly and downwardly extending portions woven in one 80 piece and adapted to form a ventilating or openwork section of a corset.

In constructing a ventilated corset, or corset having a ventilating or openwork section or sections, in accordance with my invention and improvements, I provide a piece of openwork or lattice-work comprising a series of transverse strips *a* of fabric, which are arranged, by preference, in parallel relation and a sufficient distance from each other to provide spaces *b* therebetween, all of said transverse strips being connected by means of a series of upwardly and downwardly extending, or longitudinal strips *c* which extend in perpendicular relation to 90 the transverse strips and are attached to the latter so as to hold them in proper position with relation to each other previous to and during the operation of sewing the sections of openwork or ventilating sections to the 95 main body portions *d* of the corset.

The transverse strips *a* and longitudinal or upwardly and downwardly extending strips *c* are shown in Fig. 1 formed of connected pieces of fabric which are attached to each other by means of seams *e*. They may, however, be attached by any suitable means adapted to hold them in proper relation previous to and during the operation of securing the sections to the main body por. 100 105 110

- tion or portions of the garment, although the strips may be attached by means of an adhesive material in such a manner as to enable the openwork sections to be secured 5 to the body portions of the corset, and the openwork sections may be made of transverse and upwardly and downwardly extending portions woven in an integral piece, as shown in Fig. 5.
- 10 In order to make the openwork sections of uniform construction and in commercial quantities and in the most economical manner possible a desirable method of constructing the ventilating sections is illustrated in 15 Figs. 1 and 2. A piece of openwork material, comprising transverse strips *a* and longitudinal strips *c*, is first made in any ordinary or well known manner, which is adapted to form a plurality of ventilating sections by 20 cutting the strips *c* along lines *f*, as indicated in Fig. 1. Each of the sections *g* thus formed comprises a series of transverse strips *h*, corresponding to the strips *a*, shown in Fig. 1, and side strips *i* each of which is 25 cut from one of the strips *c*—indicated in Fig. 1—with the exception that the marginal strip *j* shown in Fig. 1 is adapted to form one of the side strips of a complete section and is not required to be cut into two 30 strips in order to serve its purpose. The transverse strips *h* are provided with apertures *k* therebetween (see Figs. 2 and 3) and their opposite ends are attached to the upwardly and downwardly extending or side 35 strips *i* by means of the seams *e*, as already described in connection with Fig. 1. The transverse strips *h*, and particularly the end portions thereof, are thus adapted to be securely held in proper position with relation 40 to each other and with relation to the longitudinal or side strips *i* previous to and during the operation of securing the ventilating or openwork section or sections to the sections of the main body of the corset to 45 be connected thereby. The piece of openwork from which the sections *g* are made may also comprise in its construction upwardly and downwardly extending strips *m*, shown in Fig. 1, which extend across the 50 transverse strips *a* in parallel relation to the strips *c*, and are attached to the strips *a* and *c*, if desired, by means of the same seams *e* or the same connecting means which connect the strips *a* and *c*. These strips *m* 55 are of course adapted to be severed when the strips *c* are cut along the lines *f*, as already described, so that each forms two longitudinal strips *n* (see Fig. 3). The sections *g* comprising the transverse strips or portions 60 *h* and upwardly and downwardly extending side strips or portions *i* having been thus produced are secured to and adapted to extend across the space between the marginal edges *o* of the sections of the main body portion *d* of the garment or corset, as shown in 65 Figs. 3 and 4. The sections *g* are laid upon and in position to overlap the marginal edges *o* of the main body portions *d* of the corset, as shown in Figs. 3 and 4. A lining strip *l* is laid upon each of the strips *i* so as to provide a space or pocket *p* between the strips *i* and *l* adapted to receive a stay or strip of stiffening or reinforcing material *q* therebetween. An outer strip *r* of suitable fabric is laid upon and forms a cover for 70 the lining strip *l* and has a marginal portion *s* which projects laterally beyond the marginal edges of the strips *i* and beyond the marginal edges of the openwork sections *g* comprising the said strips *i*. This projecting portion *s* is secured to the main body portion *d* of the garment by means of a seam *t*, indicated in Figs. 3 and 4. Seams *u* and *v* are sewn through all of the strips *r*, *l*, *i* and *k* and through the inner marginal portions 75 of the garment *d* covered thereby, said seams *u* and *v* being located on opposite sides of the space or pocket *p* into which the stays *q* are inserted. The projecting portion *s* of the strip *r*, being secured at its outer margin 80 directly to the body portion of the corset, covers the unfinished outer margin of the ventilating section and aids in affording a strong and durable connection between the body portion and the ventilating section. 85 The sections *g* thus serve to connect the marginal edges of the body portions *d* of the corset, and provide ventilating apertures between said body portions *d*, and between the stays. The sections *g* being thus made complete in themselves so as to comprise transverse strips or portions *h* and upwardly and downwardly extending strips or portions integral with or attached to the transverse strips or portions by the seams *e* independently of the means for connecting the sections *g* to the body portions *d* of the corset, 90 it will be readily seen that the accurate arrangement of all of the parts in proper position, and the securing of the parts together 100 in a finished and workmanlike manner is greatly facilitated, and a uniformity of construction and symmetry of the finished product is obtained which is very durable by reason of the accurate and secure connection of the parts, and that the making of corsets economically and in commercial quantities 105 is greatly facilitated.
- I claim:
- In a corset, the combination of two body sections thereof, a ventilating section consisting of two side members laterally spaced from each other, and transverse strips having their ends secured to said side members by stitching independent of the means for securing said ventilating section to the body sections; stiffening strips extending along the said side members between their side margins, and pocket forming strips overlapping said stiffening strips and side members 110
- 120

and extending laterally beyond the latter; and means for securing the side members of said ventilating section, pocket forming strips and body portion together, comprising three laterally separated lines of stitching, the first and second lines of stitching extending through the said side members at opposite sides of said stiffening strips, and the third line of stitching 10 extending along the edge of the pocket form-

ing strip remote from the edge of the body section.

In testimony, that I claim the foregoing as my invention I affix my signature in the presence of two witnesses, this twenty-third 15 day of November, A. D. 1912.

CHARLES H. SCHOPBACH.
